[57] **CLAIM**

The ornamental design for a bed-type milling machine, as shown and described.

DESCRIPTION

FIG. 1 is a perspective view of a bed-type milling machine, showing my new design.

FIG. 2 is a side elevational view taken from the left of FIG. 1.

FIG. 3 is a front elevational view thereof.

FIG. 4 is a rear elevational view thereof.

FIG. 5 is a side elevational view taken from the right of FIG. 1.

FIG. 6 is a top plan view thereof.

FIG. 7 is a perspective view of an alternative embodiment thereof.

FIG. 8 is a side elevational view taken from the left of FIG. 7.

FIG. 9 is a front elevational view of FIG. 7.

FIG. 10 is a rear elevational view of FIG. 7.

FIG. 11 is a side elevational view taken from the right of FIG. 7.

FIG. 12 is a top plan view of FIG. 7.

The pendant-type control unit which is shown in broken lines is for illustrative purposes only.
